UNITED STATES PATENT OFFICE.

WILLIAM H. SCOTT, OF ST. LOUIS, MISSOURI.

TRUSSSED BOLSTER.

SPECIFICATION forming part of Letters Patent No. 737,160, dated August 25, 1903.

Application filed May 16, 1903. Serial No. 157,354. (No model.)

To all whom it may concern:

Be it known that I, WILLIAM H. SCOTT, a citizen of the United States, residing at St. Louis, Missouri, have invented a certain new and useful Improvement in Trussed Bolsters, of which the following is a full, clear, and exact description, such as will enable others skilled in the art to which it appertains to make and use the same, reference being had to the accompanying drawings, forming part of this specification, in which—

Figure 1 is a side elevational view, partly in section, showing one-half of a trussed bolster. Fig. 2 is a top plan view of one end of said bolster. Fig. 3 is a vertical sectional view on line 3 3 of Fig. 2. Fig. 4 is an end elevational view, and Fig. 5 is a detached view of the modification hereinafter described.

This invention relates to improvements in trussed bolsters designed for use more particularly as a truck-bolster, though it is obvious that slight modifications will adapt it for use as a body-bolster.

Referring to the drawings, A is a strut, B a compression member.

C is a tension member, and D is a head-block.

The strut and compression member are of conventional form; but the head-block D and tension member C, which contain the elements of the present invention, are arranged as follows: The head-block D is provided with the usual seat for the ends of the compression member and has projecting therefrom the flanges 1, through which bolts 2 may be projected through the flanges of the compression member to lock these parts together.

At the end of the compression member the head-block is provided with the stops 3 and 3^a, which are formed, as shown in Figs. 1 and 5, with a seat, in which laterally-projected and forwardly-extending members 4 and 4^a are placed, said members extending slightly over the end of the compression member, as best shown in the figures referred to. The head-block D is provided with the obliquely-extended passage-way or perforation projected entirely through the same from inner to outer end longitudinally of the tension member, which is threaded therethrough and bent downwardly parallel with the outer end por-

tion of the head-block, to which said tension member is riveted by means of the rivets 5, as best shown in Fig. 1. It will be observed that by reason of the peculiar construction of the head-block a rigid supporting means is provided for the ends of the compression member, the filler 6, of wedge shape, substantially filling the space between the compression member and tension member, as best shown in Fig. 1.

In order to permit of securing the down-turned end of the tension member to the end portion of the head-block, said head-block is slightly elongated beyond the usual spring-seats and hollowed out to permit of the insertion of necessary tools to be used in riveting. As the head-block is meant to be formed of malleable castings, it is cored out, as shown in the drawings, so as to provide the necessary thickness of metal to permit of proper malleation thereof.

In assembling the bolster the members 4 and 4^a are inserted in position after the compression member has been placed in its seat on the head-block, the object of said members being to more firmly hold said compression member in position.

I am aware that minor changes in the construction, arrangement, and combination of the several parts of my device can be made and substituted for those herein shown and described without in the least departing from the nature and principle of my invention.

Having thus described my invention, what I claim as new, and desire to secure by Letters Patent, is—

1. In a truss-bolster, head-blocks, seats therein for the ends of a compression member, integral seats in juxtaposition to the seats for said compression member, and removable members in said integral seats, adapted to extend over the ends of said compression member; substantially as described.

2. In a truss-bolster, head-blocks, a compression member secured thereto intermediate the ends of said member, a seat in said head-blocks, and removable means in said seat, adapted to extend over the ends of said compression member; substantially as described.

3. In a truss-bolster, head-blocks cast in one piece, having therein seats for a com-

pression member, with a perforation extending entirely through the same for a tension member, and a perforated end wall to which the tension member may be secured; substantially as described.

4. In a truss-bolster, cast-metal head-blocks having a seat, and an abutment for the end of a compression member, a tension member extending entirely through said head-blocks, 10 said tension member being bent downwardly and connected with the end walls of said head-blocks; substantially as described.

5. In a truss-bolster, a channel compression member, a flat-plate tension member, and a 15 head-block comprising a single casting provided with a seat for said compression member, and with a perforation extending entirely through the same for said tension member; substantially as described.

6. In a truss-bolster, a head-block comprising a single casting provided with a seat for a compression member and with a perforation extending entirely therethrough for a tension member, said head-block having a 20 perforated end wall; substantially as described.

25

7. In a truss-bolster, a cast-metal head-block provided with a seat for a compression member, and a seat for a tension member, and having a perforated end wall extending 30 downwardly from the tension member seat to which may be attached said tension member; substantially as described.

8. In a truss-bolster, the combination with a channel compression member, a plate tension member, and a strut, of head-blocks comprising each a single casting for coöperating with the ends of said compression and tension members, each head-block being provided with a perforation extending entirely 35 through the same, through which perforation said tension member passes, and means for retaining said tension member in place; substantially as described.

In testimony whereof I hereunto affix my 45 signature, in the presence of two witnesses, this 14th day of May, 1903.

WILLIAM H. SCOTT.
